SWINGING MECHANISM FOR ROCK DRILLS

George W. Hulshizer, Stewartsville, N. J., assignor to Ingersoll-Rand Company, New York, N. Y., a corporation of New Jersey

Application January 3, 1945, Serial No. 571,172

1 Claim. (Cl. 262—13)

This invention relates to a rock drilling apparatus, and more particularly to a swinging mechanism for rock drills used for cutting kerfs in coal deposits and the like.

One object of the invention is to expedite the swinging movement of the rock drill relatively to the working surface.

Another object is to effect the cutting of a channel or kerf with a minimum of manual effort.

Other objects will be in part obvious and in part pointed out hereinafter.

In the drawing accompanying this specification and in which similar reference numerals refer to similar parts:

Figure 1 is a plan view, partly broken away, of a rock drill, a supporting member therefor and a swinging mechanism constructed in accordance with the practice of the invention.

Figure 2 is an elevation, partly broken away, of the rock drill swinging mechanism and the supporting member.

Figure 3 is an elevation, partly in section, taken through Figure 1 on the line 3—3, and

Figure 4 is a transverse view taken through Figure 2 on the line 4—4.

Referring more particularly to the drawing, the swinging mechanism, designated in its entirety by 20, is arranged upon a supporting member 21 for swinging a rock drilling mechanism 22 back and forth along a coal bed 23 to cut a kerf 24 thereinto.

The rock drilling mechanism 22 may be of the well known drifter type comprising a rock drill 24, for actuating a working implement 26. The rock drill is slidably mounted, in a well known manner, in a shell 27 and may be actuated relatively to the shell by a feed screw 28.

The supporting member 21 may also be of a known type and is shown, for convenience of illustration, as being the lower portion of a cylindrical drill column having a base 29 provided with teeth 30 for engagement with a surface supporting the column.

The swinging mechanism 20, constructed in accordance with the practice of the invention and serving as a connection between the rock drilling mechanism 22 and the column 21, comprises a tubular body or sleeve 31 that is in telescopic engagement with the column 21 and readily rotatable thereon.

The rock drilling mechanism, more particularly the shell 27, is secured to the side of the sleeve which has an enlargement 32 with a tapered recess 33 to receive a correspondingly shaped projection 34 on the shell 27. The projection 34 is

hollow, and in an end wall 35 at the free end thereof is an aperture 36 to accommodate a bolt 37 that projects from the enlargement 32 and has a nut 38 threaded on it for drawing the tapered portion of the projection 34 into firm frictional engagement with the tapered surfaces of the recess 33. The bolt 37 is held against rotary movement within the aperture 36 by a lock nut 39 that seats against the outer end of the wall 35.

The rotary movement of the sleeve 31 on the column 21 is effected mechanically through cooperating devices carried by the column and the sleeve and including, among other elements, in the example shown, a worm gear 40 on the column 15 and a worm 41 carried by the sleeve to mesh with the worm gear. The worm gear encircles the column 21 and its hub portion 42 lies immediately above the sleeve 31 to serve as an abutment therefor. The hub portion 43 lying above 20 the gear is of sleeve-shape and is slotted longitudinally at diametrically opposed points to permit the gear to be readily clamped to the column 21 by bolts 44 in the slotted portion of the hub.

The worm 41 is arranged within a casing 45 25 lying above the enlargement 32 and joined thereto by a web 46, and in the side of the casing 45 confronting the sleeve 31 is an opening 47 to permit a segment of the gear 40 to extend into the casing for engagement with the worm 41 and to effect an interlocking engagement with the casing during the moving of the worm gear and the sleeve 31 from one position to another on the column.

At the ends of the casing 45 are flanges 48 35 having secured thereto, by bolts 49, the flanges 50 of bearings 51 and 52 for the shaft portions 53 and 54 of the worm. The bearings extend part way into the casing 45 to assure concentricity therewith and with each other, and in the bearing 51 is a thrust member 55 that acts as an abutment for the shaft portion 53 of the worm. The thrust member 55 is in the form of a screw threaded into the bearing and may, therefore, be adjusted readily to assure the correct position of the worm with respect to the casing parts. The worm 41 also carries a flange 56, at its juncture 40 with the shaft portion 54, to abut the inner end of the bearing 52 to further assure against end-wise movement of the worm with respect to the bearings.

The worm 41 is motor driven for rotating the sleeve about the column and the motor performing this service, and designated 57, is supported by a skirt 58 on the outer end of the bearing 52 to which it may be secured in any well known

manner. The motor is of the rotary pressure fluid actuated vane type, the rotor 59 of which is positioned eccentrically in a piston chamber 60 and carries radially slidible vanes 61 against which pressure fluid acts for driving it. The admission of such pressure fluid into the chamber 60 is controlled by a manually operable valve 62 having a recess 63 that is in constant communication with a pressure fluid supply conduit 64 through a passage 65 in the motor casing.

The valve 62 is rotatable in the motor casing and has a port 66 to afford communication between the recess 63 and inlet passages 67 and 68 leading to the chamber 60 at opposite sides of the point of minimum clearance between the rotor 59 and the wall of the chamber. The motor, as will, therefore, be readily apparent, is reversible for rotation in opposite hand directions, this being effected by manually oscillating the valve 62 to place the port 66 in communication with either of the inlet passages. An exhaust port, or ports, 69 is formed in the wall of the motor casing, in the zone of maximum clearance between the rotor and the wall of the chamber 60, to permit the escape of fluid to the atmosphere.

The force of the rotor 59 is transmitted by its shaft 70 and planetary gearing 71 to a carrier 72 which is interlockingly connected to a polygonally shaped end 73 of the shaft portion 54.

As will be apparent from the foregoing description, both the sleeve 31 and the worm gear 40 are shiftable longitudinally of the column 21, this being desirable to enable the rock drilling mechanism to be conveniently placed at a desired elevation with respect to the work. It will, moreover, be apparent that the worm gear and its hub portion and the sleeve 31 are so constructed and positioned that in the assembled setting of the parts the hub of the worm gear will serve as an abutment for the adjacent end of the sleeve to hold the sleeve against endwise movement in one direction relatively to the column. Movement of the sleeve in a downwardly direction is prevented by a clamp collar 74 in the form of a split sleeve having pairs of lugs 75 and 76 at the spaced ends of the sleeve, and an eye-bolt 77 pivoted on a pin 78 in the lug 75 lies between the lug 76 with its threaded end and carries a nut 79 for clamping the collar to the column.

The collar 74 is also conveniently movable longitudinally of the column, and under certain circumstances as when it is intended to lower the sleeve to its lowermost position on the column, may be removed and the lower end of the sleeve 31 may then seat upon a shoulder 80 on the base 29.

In the operation of the device, and assuming that the sleeve 31, the worm gear 40 and the collar 74 are positioned correctly upon the column 21 and with respect to each other, the rock

drill 25 is set in operation. At the same time the valve 62 is positioned to introduce pressure fluid through an inlet passage, 67 or 68, for rotating the rotor 59.

This movement of the rotor 59 is transmitted to the worm 41 by the planetary gearing and the carrier 72 and cause the sleeve and the rock drill to rotate in one direction about the column. The working implement 26 will thus be swept across the working surface to cut an arcuate kerf 24.

When the working implement has thus travelled along the working surface through an arc of predetermined length the valve 62 is shifted to place the port 66 in communication with the other inlet passage, 67 or 68. The movement of the motor will then be reversed, as will also the worm 41, and the rock drilling mechanism will swing in the opposite direction to deepen the cut in the rock surface, it being understood, of course, that during the operation of the mechanism the feed screw 28 is being rotated to actuate the rock drill and the working implement toward the work and maintain the working implement in a favorable position to receive the blows of the percussive element driving it.

This mode of operation is continued until a kerf 24 of the desired depth has been cut, that is to say, the motor is alternately reversed to cause the rock drilling mechanism to swing to and fro along the work, and after a kerf of the desired depth has been cut the rock drill is retracted on the shell 27 by means of the feed screw 28. The entire drilling mechanism, including the column 21, may then be moved to another drilling site or, if the nature of the work require, the swinging mechanism may be moved upwardly to another position on the column 21 for cutting a kerf 24 at a higher elevation.

I claim:

Swinging mechanism for rock drills, comprising a cylindrical support member, a rock drill, a working implement for the rock drill, a sleeve rotatably encircling the support member and adjustable endwise of the support member, means for connecting the rock drill to the sleeve, a casing on the sleeve having an opening in the side thereof, a worm gear to encircle the support member and to act as an abutment for one end of the sleeve and extending partly into the opening, means for securing the worm gear to the support member, a worm in the casing to mesh with the worm gear, a reversible motor on the sleeve for driving the worm and thereby swing the sleeve and the rock drill about the axis of the support member for moving the working implement to and fro along a working surface, and means adjustable on the support member to serve as an abutment for the other end of the sleeve.

GEORGE W. HULSHIZER.
